UNITED STATES PATENT OFFICE

CHARLES H. LUSH, OF FREEPORT, AND HOWARD C. WARFIELD, OF MERRICK, NEW YORK; SAID WARFIELD ASSIGNOR TO SAID LUSH

DISPENSER

Application filed September 18, 1925. Serial No. 57,115.

This invention relates to an apparatus for dispensing semi-solid or plastic materials such as lard, lubricating greases, butter, etc., but it is designed primarily for the handling 5 of ice cream.

An object of this invention is to provide a sturdy, practical and reliable apparatus for dispensing ice cream from the usual containers in a sanitary manner without the use of 10 spoons or ladles and thereby eliminating the possibility of the human hand coming into contact with the material dispensed with the consequent deleterious results.

A further object of this invention is to so 15 construct the apparatus that the elements thereof which convey and handle the material to be dispensed are insulated from the surrounding atmosphere whereby a low temperature may be maintained therein without 20 recourse to separate cooling or refrigerating means.

Another object of this invention is to make the apparatus adaptable to dispensing materials supplied in cartons composed of paper 25 or similar material without the danger of the carton or pieces thereof becoming mixed with the material dispensed and then distributed therewith. This will enable the elimination of the customary commercial 30 containers composed of wood and sheet metal which must be repeatedly washed and sterilized with the sanitary condition thereof dependent upon such washing and sterilization which is not necessary when paper cartons 35 are used since due to the cheapness thereof they can be destroyed after a single use.

A further object is to provide a conveyor 40 which is gradually and positively lowered into the material to be dispensed and which thereby ensures the continued operation of the device.

A further object is to provide means whereby the dispensing apparatus may be withdrawn from the container and contracted 45 so that the removal thereof from an exhausted container and the application thereof to a filled container is rendered facile.

Another object is to provide an apparatus 50 which will mold the extracted material to any desired form so that the material will be

in the desired shape for insertion into the retail cartons.

Another object of this invention is to provide an apparatus embodying the above mentioned features in such manner that a self-contained apparatus is secured of a construction that it may be readily and easily attached to containers and counters of the type now in general use. 55

This invention also aims to embody the 60 above mentioned features in an apparatus which is neat and attractive in appearance and which is very compact in structure so that it will occupy but very little space.

With these and other objects and purposes 65 which will be in part obvious and in part pointed out hereinafter, the invention consists in the construction, arrangement and combination of the various parts of our apparatus, whereby the objects contemplated 70 are attained as hereinafter more fully and particularly set forth, pointed out in the claims and illustrated in the accompanying drawings, in which:

Figure 1 is a vertical cross sectional view 75 of the apparatus showing the conveyor and operating shafts in fully extended position,

Figure 2 is a perspective view of the invention as applied to an ordinary counter,

Figure 3 is a cross section and part plan 80 view on the section line 3—3 of Figure 1,

Figure 4 is a cross section on the line 4—4 of Figure 1,

Figure 5 is a cross section, taken centrally and vertically, of the gathering cone and 85 lower part of conveyor screw showing the various connections thereto,

Figure 6 is a bottom plan view of the cone showing one knife or scraper in position and the other removed, 90

Figure 7 is an elevation of the carton severing knife and guide,

Figure 8 is a section of the container showing the guide groove therein,

Figure 9 is a fragmentary perspective of 95 the connection used between the various operating shafts.

Figure 10 is a central vertical cross section showing the connections between the telescoping conveying cylinders. 100

Figure 11 is a cross sectional vertical central view showing the connection between the various telescoping operating shafts, and

Figure 12 is a cross sectional view of a modified form of cone gatherer in which the knives are formed integrally upon the cone. In the following more particular description of the invention, similar reference characters refer to similar parts throughout the several views of the drawings.

Referring to the drawings, 4 indicates the usual ice cream counter provided with the usual circular openings 5 into which the containers 6 are adapted to be placed. Supported about the perimeter of the opening 5 upon the counter 4 is a cage 7 having depending arms 8 from the supporting horizontally disposed circular flange 9 which rests upon the top surface of the counter. The arms 8 at their lower ends are attached to the ring 10 which embraces and supports the container 6.

The ring 10 has a groove 11 vertically disposed therein which cooperates with the exterior surface of a longitudinally disposed groove 12 in the container 6 in order to hold the container from rotation. The groove 12 also has a further function which will be described hereinafter.

Upon the flange 9 is provided two spaced lugs 13 which serve as a bearing for the shaft 14. Upon the shaft 14 is pivoted the boss 15 which is provided at one side of the casting 16. Diametrically opposed to the boss 15 is an opening 17 provided in the horizontal flange 18 of the casting 16. A bolt 19 is secured to the flange 9 and passes through the aperture 17 and is adapted to be secured by the wing nut 20.

The upper surface of the casting 16 is provided with two spaced shoulders 21 and 22 upon which rest two spaced cylinders 23 and 24 respectively. The space between the cylinders 23 and 24 is adapted to be filled with a heat insulating substance 25 such as cork, asbestos or similar material.

At the upper portion of the apparatus and resting upon and supported by the cylinders 23 and 24 is a casting 26 which is also provided with two spaced circular shoulders 27 and 28 for cooperation with the cylinders 23 and 24. The cylinders 23 and 24 are secured to the castings 16 and 26 by any well known method such as the screws 29.

The casting 26 is provided with three vertical lugs 30, 31 and 32 which serve as bearings for the shaft 33. Upon the shaft 33 is fixed the bevel gear 34 which is positioned between the bearings 30 and 31.

Between the bearings 31 and 32 is positioned a collar 35 upon the shaft 33 and which is splined thereto by the key 36 so as to permit of sliding movement of the collar upon the shaft 33 but will prevent relative rotation between the shaft and collar. Upon the ends of

the collar are secured the bevel gears 37 and 38. A bracket 39 is secured to the bearing 31 and at the outer end thereof is pivoted an operating lever 40 which has the end 41 thereof bifurcated so as to straddle the collar 110 encircling the collar 35. Each of the legs 41 is provided with a slot 42 for cooperation with the lugs 43 upon the collar 110.

The gears 37 and 38 are adapted to drive the horizontally disposed gear 44 which is connected to the hollow drive shaft 45, by means of the plug 46. The drive shaft 45 is provided with a bearing in the casting 26. Telescoping within the drive shaft 45 are the drive shafts 47, 48 and 49 which are non-rotatively connected together by keys 50 and slots 51 as shown in Figure 9. In addition the drive shafts are kept from separation by means of the shoulders 52 and 53 as shown in Figure 11.

Shaft 49 is provided with a bearing in member 54. Below the member 54 a gear 55 is attached fixedly to the shaft 49. The member 54 also carries the guide 56 which is adapted to slide in the groove 12 of the container.

The lower end of the guide 56 is sharpened so as to form a knife blade 57 in order to sever the paper carton and to allow the guide 56 to slide in the slot 12. Attached to the casting 16 is a grooved plate 58 which is in alignment with the groove 12. The guide 56 is of sufficient length to span the distance between the plate and the container.

The gear 34 meshes with the horizontally disposed gear 59 which has attached to it drive shaft 60. Attached non-rotatively but slidably with drive shaft 60 are drive shafts 61, 62 and conveyor screw 63. These shafts and conveyor screw are connected together by the same key and slot and shoulder connections above described for shafts 45, 47, 48 and 49. A packing nut and bearing 64 is positioned in the casting 26 for the shaft 60.

Concentric with the shafts 60, 61 and 62 and the conveyor screw 63 and encircling the same at a spaced distance are the conducting cylinders 65, 67, 68 and 69. The cylinder 65 is attached fixedly to the casting 26 in any well known manner and has an elbow 70 extending at right angles thereto and leading through the cylinders 23 and 24 and the insulation 25 to the exterior of the apparatus and is provided with an opening 71 which may be of any desired configuration so as to mold the material into the shape desired. The retail carton may be placed either in or about the opening 71 to receive the dispensed ice cream and obviously the size of the retail carton will limit the amount of cream fed.

The conducting cylinders 67, 68 and 69 are exteriorly threaded as shown at 72. Secured to the lower end of each of the cylinders 65, 67 and 68 by means of set screws 73 are the collars 74 which are provided at the

lower end thereof with a constricted threaded opening 75 for threaded engagement with the next lower conducting cylinder. As will be seen in Figure 10 the upper portion of the cylinders 67, 68 and 69 have an unthreaded portion 76 in order to prevent separation of the cylinders.

The lower cylinder 69 has threaded engagement with the collar of the cone gatherer 77 as shown at 78 and is secured thereto rigidly by means of the countersunk set screw 79 although it is to be understood that any other form of fastening means may be employed. The gatherer 77 and the members attached thereto have a bearing 80 in the member 54 and directly below said bearing is a gear 81 which is adapted to mesh with gear 55. The gear 81 is rigidly attached in any well known way to the collar 82 of the cone shaped gatherer 77 and preferably bears a ratio of 5 to 1 to the gear 55 so that the gatherer will rotate slower than the conveyor screw 63 since the driving gears 34, 37, 38, 44 and 59 are preferably of the same size.

The member 77 is in the drawings shown as constructed from a solid block of metal but it is to be clearly understood that the invention also contemplates the formation thereof from wood, or any other substance or material and also as being formed hollow from sheet material.

Through the gatherer 77 and concentric with the axis thereof extend a cylindrical channel 83 the upper portion of which is threaded as before mentioned for the reception of the cylinder 69 and the lower portion is adapted for reception of the conveyor screw 63 allowing the screw to extend to the extreme lower end of the member 77 and abut the plate 84 which covers the base of the cone shaped member and closes the channel 83 at the lower end thereof. The plate 84 is secured to member 77 by the countersunk screws 85.

In the lower end of the hollow shaft of the conveyor screw 63 is a plug 86 and which is attached rigidly thereto. Into this plug is screwed a bolt 87 which passes through an opening 89 in the plate 84 and which has a large head 88 so that when the apparatus is lowered into a container the head of this bolt makes contact first with the bottom of the container and will therefore prevent the knives 90 carried by the member 77 from injuring the container or scraping up portions of the paper carton when a paper carton is used. The opening 89 is of sufficient size so as to allow the bolt 87 to freely turn and the head of the bolt 88 does not make a binding contact with the plate 84. The only purpose of the bolt is to serve as a stop and as a trunnion for the shafts 61, 60, 62 and the shaft of the conveyor screw 63.

The knives 90 are secured to a ledge 91 formed upon the member 77 by means of

screws 92 although any other form of securing means may be used. The knives are preferably two in number and are diametrically opposed and the ends thereof extend through corresponding slots 93 formed in the plate 84 as shown in Figure 5. Each knife extends radially from the channel 83 to substantially the perimeter of the base of the member 77.

Leading from in front of each knife inwardly and upwardly in the member 77 to the channel 83 are guide channels 94 which direct the material cut or scraped off by the knives into the conveying cylinders and into position for the conveying screw to operate thereon.

The shaft 33 is shown with a crank 95 and handle 96 for the operation thereof although it is clear that a motor or other power device may be used for the operation of this invention.

It will be noted particularly that the knife 57 upon the guide 56 comes into operation a small distance behind the lowest portion of the member 77 so that when a paper carton is used the member 77 has entered the carton before the knife 57 severs the carton to permit the guide to follow the groove 12. The base of the member 77 has approximately the same cross section as the carton and will therefore hold the paper carton after it has been severed closely against the wall of the container and thereby prevent it from getting into the path of the knives 90. By making the base of the size indicated it is evident that the container or carton will be entirely emptied since the knives can reach practically every portion of the container.

The casting 26 is furnished with a circular shoulder upon which rests a semi-spherical cover 97 and which is secured to the casting by screws 98. The cover is provided with a slot 99 for the lever 40 and an aperture 100 for the shaft 33. These are the only openings in the cover and it will be noted that the casting 26 prevents air entering therethrough from entering the chamber which is open to the material dispensed. The opening 71 is also adapted to be provided with a cap or plug in order to seal this opening when the apparatus is not in use thereby thoroughly insulating the main operating chamber. The cap or plug for the opening 71 is not shown since the construction thereof is perfectly obvious.

The container 6 is sustained upon the ring 10 by means of a circular bead 101 with which containers of this type are provided.

The operation of the device is as follows. The cage 7 is first positioned in the opening 5 and secured to the counter in any desired manner such as screws passing through the flange 9 thereof and penetrating the counter as shown at 102. The container is then placed in the ring 10 with the groove 12 thereof fitting into the slot 11 of the ring. The dis-

penser with the various shafts in contracted position and also with the conducting cylinders in contracted position is then pivotally connected to the flange 9 at 14 and clamped to the flange 9 by wing nut 20.

Upon rotating the shaft 33 with the gear 38 meshing with the gear 44 a gradual unscrewing of the conducting cylinders will take place with a consequent lowering of the cone shaped gatherer into the material due to the rotation of the gear 81 by the gear 55. At the same time the conveying screw 63 will be rotated at a faster speed through the medium of gears 34 and 59 and the shafts 60, 15 61 and 62.

The knives and the channels 94 will direct the material to the conveying screw and then it will be conducted and forced upward to the outlet 71 to which the retail cartons may be 20 attached for receiving it.

When the bottom of the container is reached or when for any reason it is desirous to inspect or repair the apparatus the lever 40 is thrown so as to bring the gear 37 into 25 mesh with the gear 44 and then by rotating the shaft 33 in the same direction as before the rotation of the shafts 45, 47, 48 and 49 will be reversed and the entire apparatus will be withdrawn into contracted position in the 30 upper portion. Then by loosening the wing nut 20 the entire dispensing apparatus may be tipped and examined or a new carton or container inserted.

In Figure 12, a modified form of gatherer is shown which is identical with that shown in Figure 5 except that the knives 103 are formed integrally upon the gatherer. In this form also it will be noted that the seats 91 are dispensed with.

Various changes may be made in the construction and arrangement of the invention above set forth without departing from the real purpose and spirit thereof and it is our intention to cover by the following claims 45 any modified forms of structure or use of mechanical equivalents which may be reasonably included within their scope.

We claim:

1. In apparatus of the class described, in 50 combination, a container for receiving a plastic material, means for conducting said material continuously to the exterior of said container and rotatable means including a cone having channels therein for forcing said material into said conducting means.

2. In apparatus of the class described in 60 combination, a container for receiving a plastic material, means for conducting said material to the exterior of the container and rotatable means including a cone carrying knives upon the base thereof for forcing said material into said conducting means, said knives having their cutting edges disposed transversely of the longitudinal axis of said 65 container.

3. In apparatus of the class described in combination, a container for receiving a plastic material, telescoping means for conducting said material to the exterior of the container and rotatable means including a screw conveyor for forcing said material through 70 said conducting means.

4. In apparatus of the class described in combination a container for receiving a plastic material, means for preventing the rotation of said container, dispensing means and means upon said container and dispensing means for guiding said dispensing means while permitting rotation thereof. 75

5. In apparatus of the class described in combination, a container for plastic material and means for conducting said material to the exterior of the container comprising movable threaded telescopic cylinders. 80

6. In apparatus of the class described in combination, a container for receiving a plastic material, means for conducting said material to the exterior of the container comprising movable threaded telescopic cylinders and means for lowering said conducting 90 means into the container.

7. In apparatus of the class described, means for gathering material, including a cone-shaped member carrying knives, means for conducting said material and independent means for taking said material from the gathering means and forcing it through said conducting means. 95

8. In apparatus of the class described, means for gathering material, including a cone-shaped member carrying knives, means for conducting said material including telescopic cylinders and independent means for taking said material from the gathering means and forcing it through said conducting means. 100

9. In apparatus of the class described, in combination, a container for receiving a plastic material, means for gathering said material centripetally including a cone-shaped member of substantially the same cross section at its base as the container, means for conducting the material and independent means for forcing the material through said conducting means. 110

10. In apparatus of the class described, a removable container for plastic material, means for holding said container from rotation, a dispensing apparatus, and means upon said container and dispensing apparatus for guiding said dispensing apparatus while allowing rotation thereof. 120

11. In apparatus of the class described, a container having a carton therein adapted to hold plastic material, means for removing said material, guide means upon said container and said removing means for said removing means and severing means for said carton to allow the operation of said guide means. 125

12. In apparatus of the class described, in combination a container having a carton therein adapted for holding a plastic material, removing means for said material and means for severing and holding said carton against the wall of the container. 5
13. In apparatus of the class described, in combination a container, for receiving a plastic material, means for dispensing said material to the exterior of the container and means including collapsible shafts for lowering said dispensing means into the material, said lowering means operating upon the lowest portion of the dispensing means. 10
14. In apparatus of the class described, a container adapted to hold a plastic material, means for holding said container non-rotatably and rotary means for dispensing said material pivoted to said container holding means. 15
15. In apparatus of the class described, a container for receiving plastic material, means for removing said material, means for lowering said removing means into the material and means for withdrawing said removing means from the material while the main drive shaft is rotating in one direction. 20
16. In apparatus of the class described, in combination a container for receiving a plastic material, means for conducting said material to the exterior of the container and means for leading the material to said conducting means including a cone-shaped member having channels and horizontally disposed knives attached to said member at the lower openings of said channels. 25
17. In apparatus of the class described, in combination a container for receiving a plastic material, means for conducting said material upwardly to the exterior of the container and reciprocating means for forcing said material through said conducting means disposed within and substantially at one extremity of said conducting means. 30
18. In apparatus of the class described, in combination a container for receiving a plastic material, means for conducting said material upwardly to the exterior of the container and reciprocating means for forcing said material through said conducting means disposed within and substantially at one extremity of said conducting means comprising a screw conveyor. 35
19. In apparatus of the class described, in combination a container for receiving a plastic material, means for conducting said material to the exterior of the container comprising telescoping threaded cylinders and means for forcing said material through said conducting means disposed within said conducting means and means for operating said forcing means extending through said conducting means. 40
20. In apparatus of the class described, in combination a container for receiving a plastic material, means for conducting said material to the exterior of the container comprising telescoping threaded cylinders and means for forcing said material through said conducting means disposed within said conducting means and means for operating said forcing means extending through said conducting means. 45
21. In a device of the class described, a cone-shaped gatherer having tubular channels therein and scraping means on said gatherer adjacent said channels. 50
22. In a device of the class described a gatherer having a central passageway, a conveyor in said passageway and said gatherer having channels leading to said passageway. 55
23. In a device of the class described, a gatherer having tubular channels formed therein and knives mounted upon said gatherer adjacent said channels and projecting part way over the openings of said channels. 60
24. A cone-shaped gatherer having a central passageway and channels leading to said passageway and cutting means upon said gatherer adjacent said channels. 65
25. A gatherer having a central aperture for the reception of conveying means, said gatherer also having channels therein communicating with said aperture, cutting means upon said gatherer adjacent said channels and means for rotating said gatherer. 70
26. In a device of the class described, a container adapted to hold plastic material, means for removing said material, rotating means for operating said removing means and means for raising or lowering said removing means while said removing means is rotating in one direction. 75
27. In a device of the class described, a container adapted to hold plastic material, means for removing said material including a gatherer and threaded telescoping cylinders and collapsible means exterior to said removing means for operating said gatherer and said threaded telescoping cylinders. 80
28. In a device of the class described, a container adapted to hold plastic material, means for removing said material including telescopic conducting means and means for forcing the material through said conducting means disposed within said telescopic conducting means and operated by means disposed within said conducting means. 85
29. In a device of the class described, a container adapted to hold plastic material, means for removing said material including gathering means, conducting means and means separate from said gathering means for forcing said material through said conducting means disposed and operated from within said conducting means and means for operating said conducting means and said gatherer disposed outside said conducting means. 90
30. In a device of the class described, a container adapted to hold plastic material, means for removing said material including 95

a plurality of externally threaded telescopic conducting cylinders and means for lowering said conducting means into the material.

31. In a device of the class described, a container, a support therefore, dispensing means pivoted to said support, an insulated casing for said dispensing means and means for withdrawing said dispensing means entirely within said casing or lowering it into said container.

32. In a device of the class described, means for gathering material, means for conducting material, means disposed within said gathering means and conducting means for forcing the material through said conducting means and collapsible means external to said gathering means and conducting means for rotating said gathering means and said conducting means.

33. In a device of the class described, means for gathering plastic material, telescopic means for conducting said material, means for forcing said material through said conducting means, telescopic means for operating said forcing means and telescopic means for operating said gathering and conducting means.

34. In a device of the class described, means for gathering plastic material, threaded telescopic means for conducting said material, a screw conveyor for forcing said material through said conducting means disposed within said conducting means, telescopic means for operating said screw conveyor and telescopic means for operating said gathering means and said conducting means.

35. In a device of the class described, a gatherer, telescopic conducting means connected to said gatherer, a screw conveyor positioned within said gatherer and telescopic operating means for said gatherer, and conducting means and telescopic operating means for said screw conveyor.

36. In a device of the class described, a support for a container, a screw conveyor axially disposed with reference to said container adapted to extend into said container, conducting means surrounding said conveyor and cooperating therewith to remove the material and means for causing relative vertical movement to one of said parts.

37. In a device of the class described, means for conducting material, a screw conveyor for forcing said material through said conducting means and means for rotating said conducting means and said conveyor at different speeds of rotation.

38. In a device of the class described, means for conducting material including telescopic cylinders, means for forcing said material through said conducting means including a screw conveyor and means for rotating said conducting means and said forcing means at different speeds of rotation.

39. In a device of the class described,

means for conducting material including telescopic cylinders, a screw conveyor disposed within said cylinders and means for rotating said conducting means and screw conveyor oppositely and at different relative speeds.

40. In a device of the class described, a container adapted to hold plastic material, means for removing said material including a gatherer and collapsible means moving with said gatherer for operating the same.

41. In a device of the class described, a container for plastic material, dispensing means including a gatherer, knives carried by said gatherer and means limiting the approach of said knives to the bottom of the container.

42. In a device of the class described, a container having a carton therein for plastic material, dispensing means for said material including a gatherer, knives upon said gatherer and means preventing contact of said knives with said carton.

43. In a device of the class described, a support, dispensing means upon said support, a casing for said dispensing means and means for withdrawing said dispensing means entirely within said casing.

44. In a device of the class described, means operating upon the top of the material in a container for dispensing material and collapsible means for operating said dispensing means.

45. In a device of the class described, means operating upon the top of the material in a container for dispensing material and collapsible means for rotating and causing longitudinal movement of said dispensing means.

46. In a device of the class described, means for dispensing material comprising cylinders threaded throughout their length of gradually increasing diameter for conducting the material and means for operating said dispensing means.

47. In a device of the class described, means for dispensing material comprising telescoping cylinders threaded throughout their length of gradually increasing diameter whereby the material cannot clog the same and means for operating said dispensing means.

48. In apparatus of the class described, in combination a container, for receiving a plastic material, means for dispensing said material to the exterior of the container and means for lowering said dispensing means into the material comprising threaded cylinders operated by a gear carried by said dispensing means and collapsible means for rotating said gear.

49. In apparatus of the class described, means including helical passageways for gathering material towards the centre of a container, means for conducting said material including telescopic cylinders and means for taking said material from the gathering

means and forcing it through said conducting means.

50. In a device of the class described, means for conducting material, means for forcing said material through said conducting means and means for oppositely rotating said conducting means and said forcing means about the same axis.

CHARLES H. LUSH.
HOWARD C. WARFIELD.
